CLAIM

The ornamental design for a finger ring tag, as shown and described.

DESCRIPTION

FIG. 1 is a perspective view of a finger ring tag showing my new design;

FIG. 2 is a front elevational view thereof, the rear elevational view being a mirror image thereof;

FIG. 3 is a side elevational view thereof, the opposite side elevation being a mirror image thereof;

FIG. 4 is a top plan view thereof; and,

FIG. 5 is a bottom plan view thereof.

The broken lines showing are for illustrative purposes only and form no part of the claimed design.
